United States Patent Office

Des. 218,090
Patented July 21, 1970

218,090

WALL PANEL

John Inglis, 142 Cottage St., Trumbull, Conn. 06611

Filed Feb. 19, 1968, Ser. No. 10,624

Term of patent 14 years

Int. Cl. D25—01

U.S. Cl. D13—1

The figure is a perspective view of my new design.
The backside of the panel (not shown) is plain or natural.

I claim:

The ornamental design for a wall panel, substantially as shown and described.
